UNITED STATES PATENT OFFICE.

ERNEST E. SCHENK, OF WEBSTER CITY, IOWA.

TRANSLATIONAL SECTIONAL-MOLD ASSEMBLAGE.

Application filed April 7, 1922. Serial No. 550,539.

To all whom it may concern:

Be it known that I, ERNEST E. SCHENK, a citizen of the United States of America, and a resident of Webster City, Hamilton County, Iowa, have invented certain new and useful Improvements in Translational Sectional-Mold Assemblages, of which the following is a specification.

My invention relates to improvements in translational sectional mold assemblages, and the object of my improvement is to furnish sectional molds for concrete blocks, with mechanism of which certain sections of said molds are elements, the mechanism being operative to propel the assembled molds through a determined distance, then to automatically disassemble the molds while delivering the newly molded blocks.

This object I have accomplished by the means and mechanism which are herein-after described and claimed, and which are illustrated in the accompanying drawings, in which Fig. 1 is a vertical longitudinal section of said invention taken on the broken line 1—1 of Fig. 2, and Fig. 2 is a top plan of the invention with parts removed or broken away. Fig. 3 is an enlarged view of linked assembled molds with parts shown in side elevation and other parts in longitudinal vertical section or broken away. Fig. 4 is a top plan view of linked parts of the mold and carrier elements, with parts removed or in section. Fig. 5 is a cross section taken on the broken line 5—5 of said Fig. 3, and Fig. 6 is another cross section taken on the broken line 6—6 of said Fig. 3. Fig. 7 is a perspective view of the bottom pallet of a mold.

The mechanism of my invention may be operatively mounted and supported in any desired supporting frame or construction, but I have not shown any such construction, in order to afford a better disclosure of the mechanism and of the associated mold assemblages.

The purpose of my invention is to supply translational sectional molds, in which, while assembled, blocks or objects may be formed or molded, of any kind or shape desired, but in the instance illustrated, to mold or shape building-blocks of cement, concrete or other materials, propelling and delivering them as formed successively.

These molds when assembled, are linked together in alinement, but the molds are

alike and each constructed of sections to provide an open top closed bottom hollow structure.

Each mold comprises a bottom pallet 8, flat, but which may be of any desired configuration, the one shown in Fig. 7 being imperforate, oblong, and having at each end diminishing notches or cut out openings 15, while preferably, though not necessarily having a plurality of depending short end and side legs 9 and 14 respectively, these being useful, after the pallet and newly formed block thereon are delivered disassembled from the other parts of the mold, in supporting the pallet on a surface raised thereabove to permit of easy manual handling and lifting of the pallet and block.

The side-walls 1 of each mold are imperforate, oblong, and have at their ends hinge-connections 3 with the ends of the alined abutting walls 1 of other molds. The pintle of each pair of hinge-connections 3 is carried across their interspace to serve as a pintle also for a vertical roller 2 without the mold. Each section 1 has at the bottom of its inner face a pair of short ledges 4 upon which the pallet 8 is supported removably.

I have supplied mechanism for translating in one direction said interlinked molds. This includes a sprocket-chain of peculiar construction, having spaced pairs of link-bars 6 which are rigidly connected by several cross-rods 5 and 13, the ends of each rod 5 projecting outwardly and serving to underlie and support the side-sections 1 of said molds. At one end of each pair of link-bars 6 the bars are brought convergingly nearer together to fit between ends of the adjacent pair of link-bars, and a pintle 33 connects said bars midway between pairs of cross-rods 13, a roller 7 being rotatably mounted on said pintle.

Referring to said Fig. 3, the numeral 12 denotes a pyramidal hollow structure formed of sheet metal, of which opposite lower end parts are shaped as sleeves enclosing a pair of cross-rods 13 between said link-bars 6, whereby each pyramid 12 or as it will be hereinafter termed end-former is rigidly mounted between the link-bars. It will also be now observed that each of the end-formers 12 serves as a projection for propelling the molds in one direction coincident with the movement in said direction

of the link-bars 6 of said sprocket-chain. When the end-former 12 is positioned as shown in Fig. 3 to become a part of the mold assemblage, it fits into the enclosing 5 notch 15 of the pallet 8 and between the inwardly projecting sloping ribs 16 of the side-walls 1, whereby an end-wall is provided for the mold adapted to form a re-entrant recess in a block 10 molded therein.

10 Like sprocket-wheels 26 and 28 are fixed rigidly on rotatable horizontal shafts 25 and 27 respectively, and have end-notched teeth to receive the rollers 7 of the link-bar chain 6.

15 At opposite sides of the link-bar chain 6 are positioned pairs of vertical rotatable shafts 17 and 21, and each pair having fixed thereon like sprocket-wheels 20 and 22 respectively with end-notched teeth which receive 20 the said rollers 2 on the mold side-sections 1. On one shaft 17 is fixed a belt-wheel 18 carrying a driving-belt 19.

The numeral 24 denotes a fixed guide-plate 25 extended horizontally below the upper reach of the link-bar sprocket-chain 6 between the sprocket-wheels 26 and 28 and serves to carry the rollers 7 in supporting the linked molds thereabove, while concrete material is being tamped or otherwise manipulated 30 within the molds. The blocks 10 formed in said molds may have trough-shaped hollows 11 formed therein when desired by means of any suitable appliance or forming means not shown.

35 The numeral 23 denotes a like pair of side-guides or bars positioned along the side-walls of the molds to be contacted by the side-rollers 2 to keep the sides 1 in place while the molds are being filled in the making 40 of said blocks, and the delivery ends of the bars 23 are made divergent to permit the linked parts 1 to be carried around the sprocket-wheels 20, while releasing the newly formed blocks, which are transported by 45 the pallets 8 to and delivered upon the endless band 31, the latter carried by rollers 30 on a rotatable shaft 29, a fixed supporting table 32 being placed under the upper reach of said band 31 to support the superincumbent blocks.

50 When the said mechanism is in motion, any desired means may be supplied to position pallets 8 upon the lugs 4 of the advancing side-plates 1 successively. The mold-plates or sections 1 become disassembled at the delivery ends of the guides 23 and 24, so that the pallets 8 and the blocks 10 thereon only are delivered upon the endless carrier 31. The pyramidal structures or

end-formers 12 are also withdrawn at the same time as the link-bars 6 pass about the sprocket-wheel 26 downwardly.

It is to be understood that various modifications or substitutions made in this device are nevertheless covered by my invention and are within the full scope of its protection.

Having described my invention, what I claim as new and desire to secure by Letters Patent, is:

1. In mechanism of the character described, separably assembled and engaged, and longitudinally aligned molds, and translational means therefor including projections thereon insertible between and withdrawable from the molds to close the ends of the molds.

2. In mechanism of the character described, separably assembled sectional molds open at the ends, translational devices therefor having driving projections insertible between the molds to close their ends and to suitably shape the ends of blocks formed in the molds, and means for holding said mold-sections in engagement during a determined part only of their movement of assembled translation.

3. In mechanism of the character described, separably assembled and engaged mold-sections, a plurality of translational devices operatively connected with different like aligned mold-sections for simultaneous coaction therewith, and guides for maintaining said mold-sections in a desired relation during a part only of their translatory movement as an assemblage, certain of said mold-sections serving as pallets and automatically separating from the other mold-sections when said assemblage has left said guides, and shaper elements of the molds mounted on certain of said translational devices and withdrawable from the molds at a certain stage of movement of said devices.

4. In mechanism of the character described, separably assembled and engaged mold-sections, a plurality of translational devices operatively connected with different like aligned mold-sections for simultaneous coaction therewith, certain of said mold-sections shaped to interlock and serving as pallets and block-forming end-closures and automatically separating from the other mold-sections at certain successive stages of movement of said translational devices.

Signed at Waterloo, Iowa, this 28th day of March, 1922.

ERNEST E. SCHENK.
